US00D911935S

(12) **United States Design Patent** (10) **Patent No.:** **US D911,935 S**
(45) **Date of Patent:** **** Mar. 2, 2021**

(54) **INVERTER GENERATOR**

(71) Applicant: **FNA Group, inc.**, Pleasant Prairie, WI (US)

(72) Inventors: **Gus Alexander**, Inverness, IL (US); **Christopher C. Alexander**, Park Ridge, IL (US)

(73) Assignee: **FNA Group, Inc.**, Pleasant Prairie, WI (US)

(**) Term: **15 Years**

(21) Appl. No.: **29/677,294**

(22) Filed: **Jan. 18, 2019**

(51) **LOC (13) Cl.** **13-02**

(57) **CLAIM**

The ornamental design for an inverter generator, as shown and described.

DESCRIPTION

FIG. 1 is a top-front-right perspective view of a inverter generator;

FIG. 2 is a bottom-rear-right perspective view thereof;

FIG. 3 is a top-rear-left perspective view thereof;

FIG. 4 is a front-left-bottom perspective view thereof;

FIG. 5 is a front elevation view thereof;

FIG. 6 is a rear elevation view thereof;

FIG. 7 is a right elevation view thereof;

FIG. 8 is a left elevation view thereof;

FIG. 9 is a top plan view thereof; and,

FIG. 10 is a bottom plan view thereof.

The broken lines are included for the purpose of illustrating portions of the inverter generator that form no part of the claimed design.

1 Claim, 10 Drawing Sheets
